[57] CLAIM

The ornamental design for a sofabed, as shown and described.

DESCRIPTION

FIG. 1 is a perspective view of a sofabed showing my new design;

FIG. 2 is a front elevational view;

FIG. 3 is a left side elevational view, the right side being a mirror image thereof;

FIG. 4 is a rear elevational view;

FIG. 5 is a top plan view; and,

FIG. 6 is a bottom plan view thereof.

The schematic depiction of fabric shown in FIGS. 1, 2, 4, and 5 is continuous throughout.

FIG. 2

FIG. 3

FIG. 4

FIG. 5

FIG. 6
